CABINET FOR PHONOGRAFS

Theodore H. Beard, Leland D. Norton, and John E. Renholdt, Bridgeport, Conn., assignors to Dictaphone Corporation, New York, N. Y., a corporation of New York

Application March 2, 1935, Serial No. 9,058

14 Claims. (Cl. 274—2)

This invention relates to cabinets for phonographs and more particularly to a cabinet for supporting, protecting and making conveniently operable a commercial phonograph for recording dictation.

One of the objects is to provide a cabinet of the character described, the upper portion of which is open to the front to give access to the machine supported within, the cabinet having a closure which, when shut, conforms to the general contour of the cabinet, completely enclosing and protecting the machine from dust and injury, and to employ therewith a machine support movable within the cabinet to facilitate the unobstructed manipulation of the closure and the convenient operation of the machine.

A further object is to provide simple and effective means for shifting the said support in response to manipulation of the cabinet closure. A further object is to provide means for rendering the machine operable or inoperable according as the closure occupies an open or a closed position.

A further object is to provide a cabinet of the character described provided with simple and convenient means for supporting and retaining papers, such as letters or other documents, within the cabinet.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of our invention:

Fig. 1 is a front elevation of the cabinet showing the closure for the phonograph chamber in open position, in which position access may be conveniently had to the phonograph for operation of the same. This figure also shows the lower portion of the cabinet with doors open, in which position they give access to a rack for supporting record-cylinders, portions of the rack being broken away to show certain electrical connections and equipment;

Fig. 2 is a cross-section on line 2—2 of Fig. 1 with the closure for the upper portion and the doors for the lower portion in shut position, the open position of the closure for the phonograph chamber being shown in dot-and-dash lines;

Fig. 3 is an enlarged front elevation of the phonograph support and operating mechanism therefor;

Fig. 4 is an upper plan view of the same;

Fig. 5 is a bottom plan view of a portion of the construction shown in Figs. 3 and 4.

Fig. 6 is a partial cross-section taken on line 6—6 of Fig. 1; and

Fig. 7 is an enlarged section taken on line 7—7 of Fig. 4.

Referring to the drawings, in which similar reference characters refer to similar parts throughout the different views, a phonograph cabinet is shown comprising a base 10, a lower accessory container section or chamber 11 and an upper phonograph container section or chamber 12. The base 10 may be formed of sheet metal, preferably iron or steel, die-pressed to the desired shape. Section 11 may also be made from sheet iron or steel die-pressed in one or more parts and joined in any suitable manner, as by welding. Preferably the parts are welded together, the joints ground smooth and the whole suitably enameled. This said lower section 11 is formed in the shape of a rectangular box of a width greater than its depth and of a height greater than its width, and comprises a back plate 13, side plates 14, 15, and front plate 16. Front plate 16 is provided with a large rectangular opening 17 to the side edges of which are hinged a pair of folding doors 18, 19, each provided with a handle 20 and normally held in closed position, as shown in Fig. 2, by means of spring detent members 21. Beneath the base 10 are mounted suitable casters 22 and above the base 10 within the chamber 11 is provided a shelf 23, which may conveniently be used for the storage of various phonograph accessories and equipment.

Within the lower portion of the cabinet, behind the door opening 17, there is provided a record-cylinder rack as indicated at 24. The specific form of rack illustrated herein forms, however, no part of the present invention.

It should be noted that the upper edge of the front cabinet plate 16 is at a lower level than the upper edges of back plate 13 and side plates 14 and 15. The reason for this construction will be referred to later.

Referring to Figs. 1, 2 and 6, the upper part of the cabinet enclosing the phonograph chamber comprises a rigid hooded section 33 secured to the back and side walls of the lower cabinet portion 11. This rigid hood 33 has a curved back wall 34, the lower part of which is disposed in the plane of the back plate 13 of the cabinet, the wall curving forwardly from said plane so that its upper edge 35 faces toward the front of the cabinet and lies in a plane disposed substantially midway between the front and back of the cabinet. This hooded section 33 is also provided with side walls 36 formed integrally with the curved wall 34, which extend forwardly with their front edges forming continuations of edge 35. The hooded section 33 is preferably an iron casting provided with a bead, as indicated at 37, overlapping the continuous front edge 35 of the section. Thus it

will be seen that the phonograph chamber is open to the front of the cabinet.

A hooded closure 38 is provided to complete the cabinet. This is also a casting having a curved front wall 39 and plane side walls 40, which at their lower edges terminate slightly below the line of the upper edges of the side plates 14, 15 of the lower cabinet section and extend rearwardly to meet the forwardly facing edge 35 of the rigid hooded section 33. This hooded closure, in closed position, fits within the beading 37 and abuts against the edges of the section 33. The hooded closure is of a width to permit its fitting without leaving any substantial gap between the side plates 14, 15 of the lower cabinet section. Extending rearwardly from the interior of the side walls 40 of the hooded closure 38 are a pair of lugs 41 which are pivotally mounted as at 42 interiorly of the side walls 36 of the rigid hooded section 33. A handle is furnished, as at 43, for raising and lowering the hooded closure. When swung down from the position shown in Fig. 2 to that shown in Figs. 1 and 6, the curved front of the hooded closure passes downwardly within the cabinet beneath the phonograph chamber.

Since the said closure terminates at a point above the upper edge of the front plate 16, the closure has clearance enough to assume the open position, see Fig. 6. In order that, in the closed position of the closure 38, an open space will not be left between the lower edge of the closure and the upper edge of plate 16, a flap 44 is hinged to the lower edge of the closure, as indicated at 45. Within the cabinet and supported by the rear wall 13 is a bracket 46 supporting a rubber bumper 47 adapted when the closure is swung to its lower position to engage the flap 44 and deflect it from its normal position of alignment with the hood surface 39 in order that the lower edge of said hood surface 39 may swing back to a predetermined position closely adjacent the rear wall 13 of the cabinet. One or more springs 51 normally hold flap and closure in alignment. A pair of tension springs 48 are made fast at their lower ends to the lugs 41 by means of pins 49 and their other ends are made fast to pins 50 extending inwardly from the side walls 36 of the rigid hood member 33. These springs, during movement of the hooded closure from closed to open or from open to closed position, swing past the pivots 42 and thus serve to hold the hooded closure in either open or closed position.

A rigid phonograph support or shelf is shown at 52, Figs. 2, 4 and 5. This comprises a plate 52 horizontally disposed in the cabinet at a level below the juncture of the rectangular section of the cabinet with the hooded portion. Plate 52 is bent upwardly at its sides to provide triangular supporting members 53 and is also upturned at its rear edge to provide a flange 54 which is secured to the back of the cabinet by means of screws 55. At their rear ends the sides 53 are bent toward the center line of the shelf to provide flanges 56 lying in the same plane as the flange 54, and these flanges 56 are also bolted to the back of the cabinet by means of bolts 57. The screws 55 take into the back plate 13 while the bolts 57 take into the back of the casting 33.

Movably mounted upon the shelf 52 is a carriage or movable support 58 for the phonograph. This support comprises a pair of horizontally disposed side plates 59 rigidly joined by a cross plate 60. By reference to Figs. 3, 4 and 7 it will be seen that each of the plates 59 is provided with an integrally formed ball race 61 cooperatively ar-

ranged with respect to a lower ball race 62 formed in the shelf 52. A ball bearing assembly comprising a keeper plate 63 and a plurality of ball bearings 64 is interposed between the shelf 52 and each of the carriage plates 59, with the balls in cooperative engagement with the respective ball races. By means of these bearing assemblies the carriage is slidably mounted upon the shelf so that it may move backwardly and forwardly thereon without friction. The ball keeper plates 63 prevent displacement of the individual ball bearings and are themselves permitted a certain amount of movement backwardly and forwardly with respect to the shelf, which movement is limited by means of studs 65 secured to the shelf 52 and extending upwardly through slots 66 in the keeper plates. These studs 65 also cooperate with slots 67 formed in the carriage plates 59 to limit the forward and backward movement of the carriage. The carriage is also provided with up-standing fingers 68 surrounded by suitable resilient material such as rubber tubing, as at 69, which fingers serve to hold the phonograph firmly upon the carriage. It has been thought unnecessary to show the phonograph as actually seated upon the carriage since the positioning function of the members 68, 69 is obvious. The position of the phonograph in the cabinet is, however, shown in Fig. 1. It should be noted that the corrugations forming the ball races 61 provide seats for the bottom of the phonograph casing which otherwise is unsupported by the carriage.

This invention provides means for moving the carriage forwardly to place the phonograph in convenient position for operation when the hooded closure is swung downwardly within the cabinet. The forward position is shown in Fig. 6 while Figs. 2 and 4 show the carriage in its rearward position. A pair of leaf springs 70 frictionally engage the bottom of the cross member 60 when the carriage is in its rearward position, to prevent accidental shifting thereof. The means for moving the carriage comprises a lever system, indicated generally by the numeral 71. This lever system is pivotally supported as by means of a bolt 72 upon a bracket 73 secured to the underside of the rigid shelf 52, and comprises a horizontal arm 74 extending toward the center of the shelf and closely adjacent the underside of the shelf and an arm 75 made fast at the lower end 50 of the stud 72 and extending away from the center of the shelf. To this arm 75 is pivotally secured an extension arm 76 pivoted at 77 and adjustably secured to arm 75 by means of bolt 78 and slot 79, see Fig. 5.

At its left end, as seen in Figs. 3, 4 and 5, the lever arm 74 is provided with a pin 80 extending upwardly through a curved slot 81 in the shelf 52 and through a slot 82 formed in the cross member 60 of the carriage. The right end of the lever arm extension 76 is provided with a downwardly extending stud 83 positioned in the path of movement of the hooded closure when the latter is swung to its open position and adapted to be moved rearwardly by the rear edge of said closure in such a way and to such a degree as to move the phonograph carriage forward to render the phonograph conveniently accessible and operable. A tension spring 84 extends between a pin 85, extending downwardly from the underside of the shelf 52, to the end of a pin 86 rigidly mounted with respect to the lever system. When the carriage is moved forward in response to the opening of the hooded closure, this spring is stretched and serves to return the carriage to its

rearward position when the hooded closure is again swung to its closed position.

It will be understood that the phonograph for which this cabinet is particularly adapted is an electrically-operated one wherein the phonograph drive is accomplished by means of an electric motor, a construction well known in the art. Such a phonograph is shown at 110 in Fig. 1. In order to provide electrical connections from the exterior of the cabinet to the phonograph motor the cabinet is equipped with a plug-and-socket connector 87 mounted in the back plate 13 near the base of the cabinet. This plug-and-socket connector may be connected by any suitable cord to an ordinary lighting circuit by means of a base plate or other terminal connection. A second plug-and-socket connector 88 is mounted in a bracket 89 also supported upon the rear wall 13 of the cabinet. These plug-and-socket connectors are connected by means of a cord 90 comprising a wire 91 passing directly from one contact of connector 87 to a contact of connector 88, and a wire 92 connected at one end to the other contact of connector 87 and at its other end to a contact of a switch assembly 93. Another contact of said switch is connected to a second contact of connector 88 by means of a wire 94. The connection between connector 88 and the motor may be made by means of a duplex cord 95 having suitable terminals adapted to cooperate with plug-and-socket connector 88 and a similar connector 96 on the phonograph.

The switch 93 may be of any suitable construction comprising any means for bridging the switch contacts, which means, not shown, is attached to a plunger 97. Pivotedly mounted in operative relation to this plunger, as by means of a screw 98, Fig. 2, is a lever 99, Figs. 1 and 2 having a short arm 100 adapted to engage the upper end of plunger 97 to depress the same into contact position. The lever has an upstanding arm 101 which normally tilts forwardly from a vertical position toward the front of the cabinet. This position is shown in full lines in Fig. 2. When the hooded closure 38 is swung to its open position its lower edge engages the upper end of the lever arm 101 and swings it rearwardly to the dot-and-dash position shown in Fig. 2 in which position the circuit to the motor is closed. When the hooded closure is returned to its closed position the lever 99 is swung in the opposite direction to permit the plunger 97 to return to its raised position and open the motor circuit. It will be understood that the plunger 97 is raised to its open position by any suitable spring within the switch, not shown in the present instance as such constructions are well known. A spring 109 tends to hold lever arm 101 in its forward position.

It is sometimes found convenient to keep letters or other documents within the cabinet. For this purpose in the present embodiment of the invention the rigid rear hood portion 33 has secured upon the inner surface thereof near the top a curved plate 102. This plate provides a pair of inwardly extending curved pins 103 spaced apart in a horizontal direction. The letters or other papers to be filed in the cabinet are punched near their upper edge with holes spaced similarly to the said pins. Thus the papers may be suspended from the hooks to hang down behind the phonograph. This is easily accomplished when the phonograph is in its forward position. In order that the lower ends of the suspended papers may be held closely against the back of the cabinet, 75 a retaining plate 104 is pivotally mounted as by

hinges 105 upon the rear flange 54 of the shelf 52. This plate will swing forwardly as far as the frame of the phonograph will permit when the phonograph occupies its forward position. When the phonograph moves rearwardly in the cabinet 5 the retaining plate will be shoved back against the suspended papers, thus holding them tightly in position against the back of the cabinet.

Referring again to the plate 102 it will be seen that at its upper end there extends forwardly a pair of hook members 106, see Figs. 1 and 2, which provide supports for the phonograph mouthpiece 111 and speaking tube 112, as clearly illustrated in Fig. 1. The phonograph used may be of a well-known type having a mouthpiece supporting hook 107 upon which the mouthpiece is ordinarily hung when the machine is not being used. This hook, in a manner well known in the art, is connected with a motor switch (not shown) within the phonograph in such a way that when the mouthpiece is hanging upon the hook the said motor switch is open, the switch being automatically closed upon removal of the mouthpiece from the hook to set the machine motor in operation. When the front closure of the cabinet 25 phonograph chamber is open, the phonograph will occupy its forward position in the cabinet and the cabinet switch 93 will be in a closed-circuit condition. Under such conditions, in order to use the machine, it is only necessary to take 30 the mouthpiece from the phonograph hook 107 and proceed to record in the usual manner. When the operator has no further immediate use for the phonograph the mouthpiece, instead of being replaced upon the phonograph hook 107, 35 will be supported upon the cabinet hooks 106. Under these conditions the phonograph motor would normally continue to run. However, as soon as the hooded closure for the front of the machine is swung upwardly to closed position 40 the cabinet switch 93 will be open-circuited so that operation of the phonograph motor will immediately cease. When the operator again desires to use the machine the front closure is drawn down causing the phonograph to move forwardly 45 with its carriage to a convenient position, the phonograph immediately becoming energized by the closing of the switch 93. The operator may then take the mouthpiece and speaking tube from off the hooks 106 and proceed with dictation. Should it then be desired to stop dictating 50 for a short period the mouthpiece may be returned to the phonograph switch hook 107 to disconnect the motor circuit and stop motor operation. 55

Unused or used record-cylinders may be kept in the record rack, the individual cylinders being easily withdrawn from their cartons, which are supported by the rack.

It will be seen that there is provided a construction of an essentially practical nature in which the several objects of this invention are attained.

As many possible embodiments may be made of the above invention without departing from 65 the scope thereof, it is to be understood that all matter herein set forth or shown in the accompanying drawings is to be interpreted as illustrative and not in a limiting sense.

We claim:

1. In a cabinet having a compartment open to the front of the cabinet, in combination, a closure pivoted within said compartment and adapted to swing upwardly to a position completing the enclosure of said compartment and downwardly to 75

- a position beneath said compartment to expose the interior thereof, and a shelf extending forwardly from the back of said cabinet for supporting a phonograph within said compartment.
- 5 2. In a phonograph cabinet having a compartment open to the front of the cabinet, in combination, a support defining the bottom of said compartment, a carriage for supporting a phonograph mounted movably on said support, a closure 10 pivoted within said compartment and adapted to be swung upwardly to close said compartment and downwardly beneath said support to expose the interior of said compartment, and means operable by said closure for shifting said carriage 15 forwardly upon said support when said closure is swung to its lower position.
3. In a phonograph cabinet having a compartment open to the front of the cabinet, in combination, a support defining the bottom of said compartment, a carriage for supporting a phonograph mounted movably on said support, a closure 20 pivoted within said compartment and adapted to be swung upwardly to close said compartment and downwardly beneath said support to expose 25 the interior of said compartment, means operable by said closure for shifting said carriage forwardly upon said support when said closure is swung to its lower position, and means for shifting said carriage rearwardly upon said support 30 when said closure is swung to its upper position.
4. In a cabinet having a compartment open to the front of the cabinet, in combination, a closure pivoted within said compartment and adapted to swing upwardly to a position completing the enclosure 35 of said compartment and downwardly to a position beneath said compartment to expose the interior thereof, and resilient means for holding said closure in either of its said positions.
5. In a phonograph cabinet, in combination, 40 a movable closure for the cabinet, means for supporting a phonograph within the cabinet comprising a rigid shelf and a carriage movable thereon, a frictionless bearing interposed between said shelf and carriage, means for automatically 45 shifting said carriage upon movement of said closure, and means for limiting the movement thereof.
6. In a phonograph cabinet, in combination, 50 a rigid shelf and a carriage movable thereon, a frictionless bearing assembly including a keeper plate and a plurality of balls interposed between said shelf and carriage, means for shifting said carriage, means for limiting the movement thereof, and means for limiting movement of said keeper plate.
7. In a phonograph cabinet, in combination, 55 means for supporting a phonograph comprising a rigid shelf and a carriage movable thereon, a lever pivotally mounted on said shelf, means operatively connecting said lever to said carriage, a closure pivoted on said cabinet and adapted to be moved downwardly within said cabinet to expose the interior thereof, and means on said lever positioned in the path of movement of said closure for actuating said lever to shift said carriage 65 toward the front of said cabinet.
8. In a phonograph cabinet, in combination, 70 means for supporting a phonograph comprising a rigid shelf and a carriage movable thereon, a lever pivotally mounted on said shelf, means operatively connecting said lever to said carriage, a closure pivoted on said cabinet and adapted to be moved downwardly within said cabinet to expose the interior thereof, means on said lever positioned in the path of movement of said closure for actuating said lever to shift said carriage toward the front of said cabinet.
9. In a cabinet, in combination, a horizontally disposed phonograph shelf rigidly supported within said cabinet and extending forwardly 10 from the back of said cabinet, a vertically disposed plate within said cabinet having its lower edge mounted in hinged relation to said shelf adjacent the back of the cabinet to provide a movable retaining means for papers such as letters, 15 documents, etc., and suspension means for said papers disposed above said retaining means.
10. In a cabinet having the front portion cut away to give access to the interior thereof, in combination, a closure for said cut-away front 20 comprising a hood pivotally mounted within said cabinet and a depending hinged flap, resilient means normally holding said flap in surface alignment with said hood, means for swinging said hood downwardly within said cabinet, and 25 means within said cabinet for deflecting said flap from its normal position to enable said hood to move to a predetermined position within said cabinet.
11. In combination, a cabinet, an electrically 30 operated phonograph mounted within said cabinet, an operating circuit for said phonograph, a switch mounted within said cabinet and operatively associated with said circuit, a hood mounted on said cabinet and movable to an open or 35 closed position, and switch-actuating means within said cabinet cooperatively arranged with respect to said hood to render said phonograph operable when said hood is moved to said open position.
12. In combination, a cabinet, an electrically 40 operated phonograph mounted within said cabinet, an operating circuit for said phonograph, a switch mounted within said cabinet and operatively associated with said circuit, a hood mounted on said cabinet and movable to an open or 45 closed position, switch-actuating means within said cabinet cooperatively arranged with respect to said hood to render said phonograph operable when said hood is moved to said open position, and means for actuating said switch to render said phonograph inoperable when said hood is moved to closed position.
13. In a cabinet, in combination, a movably 50 mounted support for a phonograph, means for shifting said support, an electrically operated phonograph mounted on said support, an operating circuit for said phonograph including means for controlling said circuit, and a movable closure for said cabinet adapted operatively to 55 actuate said support-shifting means and said circuit-controlling means.
14. In a cabinet having a compartment opening to the front of the cabinet, a closure pivoted within said compartment and adapted to swing 60 upwardly to a position completing the enclosure of said compartment and downwardly to a position beneath said compartment to expose the interior thereof, and means within said compartment for supporting a phonograph.

THEODORE H. BEARD.
LELAND D. NORTON.
JOHN E. RENHOLDT.
